CLAIM

The ornamental design for a pen light, as shown and described.

DESCRIPTION

FIG. 1 is a front perspective view of a pen light, showing my new design;

FIG. 2 is a rear perspective view thereof;

FIG. 3 is a front elevation view thereof, the rear elevation view being a mirror image of FIG. 3 and therefore not shown;

FIG. 4 is a left elevation view thereof;

FIG. 5 is a right elevation view thereof;

FIG. 6 is a top plan view thereof;

FIG. 7 is a bottom plan view thereof;

FIG. 8 is a partial enlarged view of FIG. 1; and,

FIG. 9 is a partial enlarged view of FIG. 2.

The evenly-spaced broken lines in the figures are for the purposes of illustrating portions of the pen light, which form no part of the claimed design; The dot-dash broken lines surrounding the enlarged views in FIGS. 1, 2, 8 and 9 are for the purpose of annotating the enlargements and form no part thereof.
